(57) CLAIM

The ornamental design for a feminine hygiene undergarment set, as shown and described.

DESCRIPTION

FIG. 1 is an isometric view of a feminine hygiene undergarment set showing the new design, showing the brassiere portion separately for ease of illustration;

FIG. 2 is a front view thereof;

FIG. 3 is arear view thereof;

FIG. 4 is a right hand side view thereof;

FIG. 5 is a left hand side view thereof;

FIG. 6 is a top view thereof;

FIG. 7 is a bottom view thereof;

FIG. 8 is an isometric view of a feminine hygiene undergarment set showing the new design, showing the panties portion separately for ease of illustration;

FIG. 9 is a front view thereof, wherein the rear view is a mirror image of the front view;

FIG. 10 is a right hand side view thereof;

FIG. 11 is a top view thereof;

FIG. 12 is a bottom view thereof; and,

FIG. 13 is an isometric view of a feminine hygiene undergarment set illustrating the brassiere portion and the panties portion together.

The broken lines shown in the drawings represent portions of the feminine hygiene undergarment set that form no part of the claimed design.
